APPARATUS FOR MANUFACTURING CIGAR
FILLERS

Franz Heinrich Benno Stelzer, Dresden, Germany, assignor to "Universelle" Cigarettenmaschinen-Fabrik, J. C. Muller & Co., Dresden, Germany

Application April 19, 1932, Serial No. 606,239, and
in Germany May 15, 1931

25 Claims. (Cl. 131—39)

In the manufacture of cigar fillers a tobacco filler is used consisting of more or less finely cut strips of tobacco. In all cases the problem is to separate a strictly definite portion from the supply of filler tobacco and work it into a filler. Numerous methods have been proposed in which the tobacco, generally already separated and before it comes into the actual filler press is invariably subjected to forcible operations.

10 These operations are extremely harmful to the condition of the filler tobacco in the filler. It is very important that the sensitive strips of filler tobacco should be kept unimpaired and not damaged or destroyed by fracture, crumbling, and the like.

By means of the present invention it is possible to allow the cut filler tobacco to pass quite loosely, without the employment of any forcible measures, from the supply to the pressing position. In the course of this operation the tobacco is exactly portioned. For this purpose the tobacco inserted loosely in a supply vessel, is passed continuously in mass to a collector vessel by means of a stirring device or the like, and 25 from the collector vessel one portion of tobacco after the other is removed by means of a measuring receptacle. A shaping channel with a shaker is provided, in which the tobacco is poured loosely and then pressed into the shape of a filler.

30 In this manner the filler tobacco is not subjected to the slightest stress by pressure, compression or the like on its passage from the supply to the filler press, it does not come into any contact whatever with mechanical separators in the form of channel pushers, rotating chambers, or the like, but it always remains in loose condition until the moment when it is formed in the 35 filler press.

It is advantageous if the material, which is fed to the sack-like container with the measuring receptacle according to my copending application Serial No. 415,295, is deposited on a circular or disc-shaped surface and thrust towards an outlet in the disc by scraper plates extending 45 radially over the stationary disc surface. The material passes through the outlets into the sack; it is obvious that the movement of the scraper must be suitably correlated to the movements of the measuring receptacle.

50 For instance, the radial scraper plates may be driven by a ratchet and pawl mechanism which is actuated by the driving mechanism of the suction head, which removes therefrom the portion of material presented by the measuring receptacle. This suction head must be brought

each time to the filled measuring receptacle so that it can remove the tobacco portion and then carry out a movement in order to deposit the portion at another place.

The disc on which the material is placed is 60 preferably the slanting bottom portion surrounding a circular groove, whilst at the tobacco outlet there is also provided a shaker rod or the like which ensures the uniform flow of the tobacco over the appropriate edge of the outlet. Here 65 again the shaking movement can be derived from the movement of the suction head in that the rod is placed on a support which is drawn by a spring against a cam connected with the suction head.

In order to ensure that the measuring receptacle always removes an uniform amount of tobacco from the sack-like supply vessel according to my copending application Serial No. 415,295, the sack-like supply vessel is preferably provided 70 with beating members which, when the lowest position of the measuring receptacle is reached, strike the outside of the fabric wall of the supply vessel. Thus the wall of tobacco resting 75 against the fabric wall of the container is driven towards the middle, so that on each occasion, above the measuring receptacle which is in its lowest position, the supply of tobacco is in an uniform layer. Further it is preferable to arrange for the beaters to be actuated by the 80 downwardly moving measuring receptacle in order thus to produce the beater action at the right moment by positive means. In this arrangement the beaters may consist of tongues attached 85 to bell crank levers, so that, when the measuring receptacle moves downwards, stops or the like fitted thereto strike the free ends of the bell crank lever and thus cause the tongues to swing 90 out.

It has been found to be particularly advantageous not to subject the entire bottom of the measuring receptacle to the action of suction air, but only the centre part of the bottom thereof. This prevents a layer of tobacco from being precipitated on the bottom of the vessel by the suction effect, which is not affected by the shaking movement, which helps the tobacco arriving above the layer in the vessel, to be driven partially back by the blows of the beater outwards over the wall of the vessel. If, on the other hand, only the central part of the bottom of the vessel is under suction, then there is formed here a core of tobacco which assumes a kind of conical form and, as experience has shown, assists in the arrangement of the rest of the tobacco. It has 100 105 110

been found that the particles of tobacco by means of the core in conjunction with the walls of the bottom of the vessel, under the blows of the shaker, are arranged in a definite manner controlled from the middle of the vessel and so remove the tendency of the particles once fixed from springing out of the measuring receptacle. The result is that a constantly uniform amount of tobacco is collected in uniform thickness in the measuring receptacle.

The invention is illustrated in the annexed drawings, in which:—

Fig. 1 is a vertical longitudinal section.

Fig. 2 is a plan, and

Figs. 3 and 4 are detailed views.

In the funnel-shaped container 1 which is attached to the base plate 2, there is arranged a cylinder 3 which is attached to the axle 4. The latter is mounted in a bearing 5 which is attached to the base plate 2. On the axle 4 is mounted a ratchet wheel 6 with which a pawl 7 engages. The latter is mounted on a pivot 8 which is attached to the lever 9. The latter is mounted on a collar on the bearing 5; the lever 9 is pivotally connected at 9' with a link 10 the other side of which is connected by a pin 11 to the disc 23 (for the sake of clarity the lever 9 is shown extended in Fig. 1). To the cylinder 3 are attached triangular plates 12 which divide the funnel-shaped space into several equal parts, in the present example into three parts. The funnel-shaped container 1 is formed with a cut-away portion 1', the discharge edge x of which is provided with a rod 13. The latter is adapted to pivot about the pin 14 of the support 18, and under the influence of a spring 17 which tends to draw the rod 13 constantly towards a pin 16 in a slot 15 and fixed in the support 18. The latter is pivotally mounted on a bolt 18a. By the outward swinging movement of the suction head 20 towards the container 1, as indicated in full lines, the finger 19 comes into contact with the support 18 so that the rod 13 comes into contact with the tobacco from below and promotes an uniform deposition of the tobacco. The suction head is connected by a hollow arm 21 with an axle 22 formed by a pipe or the like. On this axle 22 there is also mounted a disc 23 to which the pin 11 is attached.

In the container 24, by means of the ring 25, there is secured a cloth 26, the outer side of which is attached to the measuring receptacle 27 and serves as a collecting vessel (cf. U. S. Patent Serial No. 415,295). The measuring receptacle 27 is provided with a perforated bottom 28 to which is connected a suction piping consisting of a rubber pipe 29. The measuring receptacle is attached to a rod 30 which is mounted at 31 and 31'' on the machine frame 32 so as to be vertically displaceable. The bottom part of the rod 30 is provided with a groove 30' in which a spring wedge, provided in the bushing 31' of the bearing 31'', engages. The bushing 31' is turned to and fro by the crank disc 31''. On the rod 30 there is mounted a sleeve 33 which is provided with flanges in which a roller 34 of a rocker lever 35 engages. The rocker lever is mounted at 36 on the bracket 32 and is provided with a slot guide 35'. In this slot guide 35' there engages a crank pin 37, which is provided with a roller, and which is mounted on a crank disc 38. The latter is mounted on a shaft 39 which is connected with a driving mechanism not shown in the drawings. The shaft 39 imparts

in known manner a periodical swinging movement to the axle 22.

At the right end position of the suction head 20 indicated by dotted lines in Figs. 1 and 2, is arranged a funnel 40, the mouth of which is provided with a channel 41 of U-shaped cross-section and bent into a semi-circle. Both sides of this channel 41 end in two downwardly directed funnel-shaped members 41'. Under each of the members 41' there is arranged a pressure chamber 42 in which, by means of a plunger 43, the tobacco filler is formed. The channel 41 is provided with a plate 45 which is mounted on an arm 46. The latter is mounted on an axle 47, which by means of a cam 47' is swung periodically to and fro in such manner that the tobacco which passes through the funnel 40 into the channel 41 is fed alternately to the two pressure channels 42 by the plate 45.

The apparatus operates in the following manner.

The tobacco inserted by hand, conveyer belts or the like into the funnel-shaped container 1, is, by means of the plates or wings 12 which are set into slow rotation by the link 10 and the pawl 7, passed towards the cut-away portion 1', through which it falls down on to the cloth 26. The rod 13 which is swung up and down by the suction head 20, ensures that the tobacco flows down uniformly through the outlet 1'. Thus the supply of tobacco held in the cloth 26 is correspondingly supplemented on its removal by the measuring receptacle. When the receptacle 27 moves downwards, which takes place during the continuous turning to and fro (shaking) the receptacle 27 is filled with tobacco which is always held in incompact and loose condition. On the upward movement of the receptacle which also takes place during continuous turning to and fro the parts of tobacco lying over the edge 115 of the receptacle are shaken down and returned to the supply of tobacco in the cloth 26. The suction action exerted on the receptacle 27 by the suction piping 29 ensures an easy "anchoring" of a suitable quantity of tobacco threads 120 within the receptacle. It should be noted that the suction action produced by the pipe 29 is only sufficient to ensure that the tobacco held in the receptacle is incompact and loose, and that the formation of lumps, which might easily prevent 125 uniform separation, is prevented.

As already mentioned, the rotation of the plates 12 in the container 1 is so arranged that on all occasions only so much tobacco is delivered to the cloth as is removed by the suction head. By exact regulation of the movement which is transmitted by the pawl 7 to the ratchet wheel 6, this can be done with a certain amount of accuracy. However, in order to keep the supply in the cloth uniform in all cases, the cloth 26 is provided with an opening 26' through which in all cases the tobacco slides down over the slide-way 49 into a collecting vessel 50, when too much is delivered into the cloth 26 from the container 1.

As soon as the measuring receptacle 27 arrives in the upper position (that is the position indicated in full lines in Fig. 1), the suction head 20 which is then in the position indicated by dotted lines in Fig. 1, is subjected to suction. The tobacco is thereby removed from the measuring receptacle 27 and drawn towards the perforated surface 20' of the suction head 20. It is obvious that in this operation the suction action in the piping 29 must be interrupted or changed into

pressure action. Whilst the measuring receptacle 27 then moves downwards in order to be filled again, the suction head 20 is moved into the right-hand position indicated by dotted lines in Fig. 1. During this movement the suction head is passed over a rotating raking roller 44 which removes the protruding threads of tobacco from the suction head 20. Then the suction action of the suction head 20 is interrupted so that the tobacco can be passed through the funnel 40 into the channel 41. From the latter the tobacco, still in loose condition, passes into the appropriate pressing channel 42. Then the tobacco first comes into contact with an oscillating flap 48 which acts upon the individual tobacco strips in such manner that they come into position substantially transversely to the longitudinal direction of the pressure channel 42.

In all the arrangements described above importance has been attached to the fact that the tobacco is always in a loose and incompact condition. Only upon arrival in the pressure channel 42 itself is the portion of tobacco compressed into a tobacco-filling.

For the sake of convenience, as shown in Fig. 3, the sack-shaped supply container 26 may be provided with brackets 45, on which bell crank levers 47 are pivoted at 46. Whereas one end of each bell crank lever extends beneath the boss 27' of the measuring receptacle 27, the other ends of the bell crank levers are provided with beaters in the form of tongues 48.

When the measuring receptacle 27 moves downwards, the boss 27' of the measuring receptacle 27 comes into contact with the free ends of the bell crank levers 47, whereby the tongues 48 fixed thereto beat against the cloth wall 26. When the measuring receptacle moves upwards the bell crank levers rest against stops 49 which are provided on the brackets 45. In order to be able to adjust the amplitude of the oscillation of the tongues 48 and therefore their beating action, adjusting screws 49' are provided on the stops 49. By the beating of the tongues 48 against the cloth wall 26 the annular wall of tobacco formed therein on the downward movement of the measuring receptacle is demolished.

In the form of construction shown in Figs. 1 and 2, the entire base of the measuring receptacle is perforated. It is, however, preferable to insert in the measuring receptacle 27—as shown in Fig. 4—a curved bottom 50, the central portion 50' of this being provided with an opening which is connected with a junction piece 51 for the suction piping 29. The core of tobacco formed in the middle of the measuring receptacle by the current of suction air provides a point of support for the other threads of tobacco.

Having thus described the nature of the said invention and the best means I know of carrying the same into practical effect, I claim:

1. An apparatus for manufacturing cigar fillers comprising a tobacco supply container for loose filler tobacco, a tobacco collector, means for removing from said collector predetermined amounts of loose tobacco, means for feeding tobacco from said supply container to said collector and means for compressing said tobacco removed from said collector into the shape of a filler.

2. An apparatus for manufacturing cigar fillers comprising a supply container for loose tobacco, a loose tobacco collector, means for removing from said collector predetermined amounts of loose tobacco, rotary means in said supply container for feeding loose tobacco from said supply

container to said collector and means forming said tobacco removed from said collector into the shape of a filler.

3. An apparatus for manufacturing cigar fillers comprising a supply container for loose tobacco, a collector, means for removing from said collector predetermined amounts of loose tobacco, means for feeding loose tobacco from said supply container to said collector, a shaping channel, a beater associated with said shaping channel and means for feeding said tobacco in loose condition removed from said collector to said shaping channel.

4. An apparatus for manufacturing cigar fillers comprising a supply container having an opening at one side thereof, a collector above which said opening extends, rotary means in said supply container for feeding loose tobacco towards said opening and into said collector, means for removing predetermined amounts of loose tobacco from said collector and means for forming said removed portions of tobacco into a cigar filler.

5. An apparatus for manufacturing cigar fillers comprising a supply container for loose tobacco having an opening disposed at one side thereof, a collector for loose tobacco disposed so as to receive the tobacco passing through said opening, means for removing predetermined amounts of tobacco from said collector, a rotary feeding means in said supply container for feeding said loose tobacco towards said opening, means for regulating the amount of tobacco fed from said supply container and means for forming said tobacco removed from said collector into a cigar filler.

6. An apparatus for manufacturing cigar fillers comprising a supply container for loose tobacco having an opening therein, a collector disposed so as to receive tobacco passing through said opening, means for removing predetermined amounts of said tobacco from said collector, rotary feeding means for the loose tobacco in said supply container adapted to feed said loose tobacco towards said opening, means for regulating said feeding means in said supply container and means for forming said tobacco removed from said collector into a cigar filler.

7. An apparatus for manufacturing cigar fillers comprising a supply container for loose tobacco having an opening disposed at one side thereof, a collector positioned so as to receive tobacco fed through said opening, means in said supply container for feeding loose tobacco towards said opening, means associated with said supply container for agitating said loose tobacco as said tobacco is fed through said opening, means for removing predetermined amounts of tobacco from said collector and means for forming said loose tobacco into a cigar filler.

8. An apparatus for manufacturing cigar fillers comprising a supply container having an opening at one side thereof, a collector positioned so as to receive tobacco when fed through said opening, means for removing predetermined amounts of tobacco from said collector, intermittently operated means in said supply container for feeding said loose tobacco through said opening, means associated with said supply container for breaking up the tobacco as fed through said opening and means for forming said loose tobacco removed from said collector into a cigar filler.

9. An apparatus for manufacturing cigar fillers comprising a supply container for loose tobacco, means for feeding said loose tobacco from said supply container in predetermined amounts, a collector to receive the tobacco fed from said con-

- tainer, means for separating from said tobacco in said collector a predetermined amount and means for transferring said predetermined amount to a cigar filler shaping mechanism.
- 5 10. An apparatus for manufacturing cigar fillers comprising a supply container for loose tobacco, a collector, means for feeding loose tobacco in predetermined amounts from said supply container to said collector, reciprocating means associated with said collector for separating from the tobacco in said collector a predetermined amount of loose tobacco, cigar filler shaping mechanism and means for removing said predetermined amount of tobacco separated in said collector to said shaping mechanism. 80
- 10 11. An apparatus for manufacturing cigar fillers comprising a supply container for loose tobacco, a collector, means for feeding loose tobacco in predetermined amounts from said supply container to said collector, means for separating a predetermined amount of loose tobacco in said collector, means for reciprocating said separating means, means for oscillating said separating means, a cigar filler shaping mechanism and means for removing said predetermined amount of tobacco separated by said separating means to said shaping mechanism. 85
- 20 12. An apparatus for manufacturing cigar fillers comprising a supply container for loose tobacco, a flexible collecting vessel located adjacent said supply container, means for feeding loose tobacco from said supply container to said collector, a reciprocating separating mechanism associated with said collecting vessel so as to separate a predetermined amount of tobacco from the loose tobacco in said collector, cigar filler shaping mechanism and means for removing said separated predetermined amount of tobacco from said collector to said shaping mechanism. 90
- 30 13. An apparatus for manufacturing cigar fillers comprising a supply container for loose tobacco, means for feeding loose tobacco from said supply container, a collector adapted to receive the loose tobacco from said supply container, a pneumatic separating mechanism associated with said collector for separating a predetermined amount of tobacco from the loose tobacco in said collector, a cigar filler shaping mechanism and means for removing said separated portion of tobacco from said collector to said shaping mechanism. 95
- 40 14. An apparatus for manufacturing cigar fillers comprising a supply container for loose tobacco, means for feeding said loose tobacco from said supply container, a collector for receiving tobacco fed from said supply container, means for removing a predetermined amount of loose tobacco from said collector, means associated with said supply container for breaking up said tobacco as it is fed from said supply container to said collector, said last named means being operated by said removing means and means for shaping said removed tobacco from said collector into a cigar filler. 100
- 50 15. An apparatus for manufacturing cigar fillers comprising a supply container for loose tobacco, a collector adapted to receive the tobacco fed from said supply container, means for feeding tobacco from said supply container to said collector in predetermined amounts, a reciprocating and oscillating separating means associated with said collector for removing amounts of tobacco substantially equal to the amounts of tobacco fed to said collector from said supply 105
- 60 container, means for removing said separated portions of tobacco and means for forming the same into a cigar filler. 110
- 70 16. An apparatus for manufacturing cigar fillers comprising a supply container for loose tobacco, radial plates disposed in said container, means for rotating said radial plates so as to feed said loose tobacco in said container to a discharge opening, means associated with said container for breaking up said tobacco as it is fed through said discharge opening, a collector adapted to receive the tobacco from said supply container, means for separating and removing predetermined amounts of tobacco from said collector and means for forming said removed tobacco into a cigar filler. 115
- 80 17. An apparatus for manufacturing cigar fillers comprising supply container for loose tobacco, a collector, means for feeding said loose tobacco from said container to said collector, means for removing predetermined amounts of tobacco from said collector, means for operating said removing means and said feeding means of said supply container in unison and means for forming said removed portions of tobacco 120 into a cigar filler. 125
- 90 18. An apparatus for manufacturing cigar fillers comprising supply container for loose tobacco having an opening therein, a rotary member located in said supply container, radial plates extending from said rotary member dividing said supply container into a series of chambers of substantially equal capacity, means for rotating said rotary member so as to discharge the contents of said chambers through said opening, a collector adapted to receive the tobacco as discharged from said opening, separating means associated with said collector for separating predetermined amounts of tobacco from the tobacco in said collector, means for removing said separated portions of tobacco and means for forming said separated portions into a cigar filler. 130
- 100 19. An apparatus for manufacturing cigar fillers comprising a supply container for loose tobacco having an opening, a shaker rod upon said container acting at said opening to separate further the loose tobacco, a collector adapted to receive the tobacco from said supply container, pneumatic removing means for removing a predetermined amount of tobacco from said collector, said removing means actuating said shaker rod and means for forming said removed tobacco into a cigar filler. 135
- 110 20. An apparatus for manufacturing cigar fillers comprising a supply container for loose tobacco, a collector of flexible material into which the loose tobacco is fed from said container, reciprocating pneumatic means associated with said collector for separating predetermined amounts of tobacco from the tobacco in said collector, beaters associated with said flexible collector operated by the movements of said pneumatic separating means, means for removing said separated portions of tobacco and means for forming said separated portions into a cigar filler. 140
- 120 21. An apparatus for manufacturing cigar fillers comprising a supply container for loose tobacco, means for feeding tobacco from said supply container, a collector adapted to receive the tobacco fed from said container, the walls of said collector being formed of flexible material, pivoted beating rods disposed below the walls of said flexible collector, a reciprocating separator for separating predetermined amounts of tobacco 145
- 130

- from the tobacco in said collector, said beaters being operated by the reciprocating motion of the separator, removing means for removing the separated portions of tobacco and means for forming the separated portions into a cigar filler. 5
22. An apparatus for manufacturing cigar fillers comprising a supply container for loose tobacco, a collector of flexible material located adjacent said container, means for feeding loose tobacco from said container to said collector, separating means associated with said collector for separating predetermined amounts of tobacco from the tobacco in said collector and means for agitating the tobacco in said collector operated by 10
- 15 said separating means.
23. An apparatus for manufacturing cigar fillers comprising a supply container for loose tobacco, a collector for the loose tobacco, means for feeding loose tobacco from said container to said 20 collector and means associated with said collector for separating predetermined amounts of tobacco from the tobacco in said collector and forming the same into a cigar filler.
24. An apparatus for manufacturing cigar fillers comprising a supply container for loose tobacco, a collector, means associated with said 25
